HINGE

Oscar Schreiber, Wingdale, N. Y.

Application July 27, 1935, Serial No. 33,514

3 Claims. (CL. 16—176)

This invention relates to hinges and more particularly to so-called loose pin hinges in which hinge straps having aligned knuckles are held together by hinge pins extending longitudinally through the hollow knuckles.

Heretofore, in hinges of this type movement of the parts in use tended to gradually work the pin out of position, producing an unsightly appearance and ultimately permitting separation of the parts.

An object of this invention is to provide a hinge of the type set forth constructed and arranged to resist any tendency to expel the hinge pin resulting from operation of the parts, while yet permitting quick and easy assembling or disassembling thereof.

This and other objects which will be apparent to those skilled in the art are accomplished by the present invention, one embodiment of which is illustrated in the accompanying drawing in which,

Fig. 1 is a view in elevation of a hinge assembly constructed in accordance with one embodiment of my invention;

Fig. 2 is a transverse sectional view on the line 2—2 of Fig. 1 showing the parts in locked position; and

Fig. 3 is a similar view showing the parts in position to permit separation thereof.

The particular embodiment of this invention which has been chosen for the purposes of illustration comprises a hinge having straps 5 and 6, the strap 5 having spaced hollow knuckles 7 and 8 and the strap 6 having a centrally located hollow knuckle 9 adapted to be located between the knuckles 7 and 8. It will, of course, be understood that the present invention is equally adaptable to hinges having any desired arrangement or number of knuckles.

In the present invention, the hinge pin is constructed and arranged to resist any tendency to work out of operative position, and provision is made for preventing complete removal of the pin from the associated parts without, however, preventing intentional separation of the hinge straps. As illustrated, the pin is sectional. Each section is separately mounted in one of the hinge knuckles and means is provided for limiting the longitudinal movement of each section and preventing removal thereof from the associated knuckle.

In the illustrated embodiment, the pin section 10 is located in the upper knuckle 7 of the strap 5. It may or may not have an ornamental head 11. A stud 12 extends through the side wall of

the knuckle and projects into a key slot, groove, or the like 13 so as to permit limited longitudinal movement of the pin section 10 while preventing removal thereof from the knuckle.

An intermediate pin section 14 is mounted in the knuckle 9 of the hinge strap 6 and a stud 15 or the like extending through the side wall of the knuckle engages a key slot 16 to permit limited longitudinal movement of the pin in the knuckle. A bottom pin section 17 is similarly located in the lower knuckle 8 of the strap 5, and is similarly held in place by a stud 18 extending through the wall of the knuckle and projecting into a key slot or groove 19 in the pin section.

Assuming that the pin sections have been assembled in different knuckles, the separate hinge straps 5 and 6 are connected by positioning each pin section so that its lower end is withdrawn within the associated knuckle. The pin section 14, which is located in the intermediate knuckle 9, is of such length as to be capable of being located entirely within the knuckle. The top pin section 10 is raised so as to withdraw its lower projecting end to within the knuckle 7, whereupon the hinge straps 5 and 6 can be positioned with the knuckles in alignment. Driving the upper pin section 10 downwardly projects its lower end into the adjacent knuckle 9, and in turn drives the pin section 14 in the intermediate knuckle 9 downwardly into the bore of the knuckle 8. The lower end of the bottom pin section 17 projects downwardly as shown in Fig. 2, so that the lower end is accessible.

When it is desired to detach the hinge straps 5 and 6, the projecting end of the lower pin section 17 is driven upwardly. This raises the pin sections 14 and 10 to the positions shown in Fig. 3, permitting separation of the hinge straps.

Although the slots 13, 16 and 19 may be of any desired form, they are preferably in the form of key slots which permit longitudinal movement of the pin sections in the knuckles, while preventing any relative rotation so as to reduce any tendency of the pin sections to work out of the knuckles as a result of operation of the hinge.

Although I have described in specific detail the preferred embodiment of my invention, it will be apparent that the invention can be variously modified and adapted within the scope of the appended claims.

I claim:

1. The combination in a hinge of separate straps having aligned knuckles, a sectional hinge pin having a section of such length in each

knuckle as to be movable into position to permit assembly or disassembly of the hinge straps, or into position to project within an adjacent knuckle to hold said straps together, and means 5 for limiting the longitudinal movement of said pin sections relative to said knuckles.

2. The combination in a hinge of separate straps having aligned knuckles, a sectional hinge pin having a section in each knuckle movable into position to permit assembly or disassembly of the hinge straps, or into position to engage within an adjacent knuckle to hold said straps together, said pin sections being in abutting relationship, and a projecting end on an end 10 section for use in causing longitudinal movement of each pin section relative to said knuckles.

3. A hinge, comprising two leaves, one formed

with two spaced knuckles and the other with a single knuckle adapted to be aligned with said spaced knuckles in the space between the same, and a pintle made in three separate sections adapted to be placed in said knuckles in abutting positions, the section placed in said single knuckle and the section placed in one of said spaced knuckles being of the same length as said knuckles, the section placed in the other of said spaced knuckles being of greater length 10 than its knuckle so as to enable it to protrude beyond the inner end of said knuckle when moved in one direction to thereby displace the pintle section in said single knuckle to extend into the adjacent other knuckle of said spaced 15 knuckles.

OSCAR SCHREIBER.
